Primary Examiner — Ruth McInroy(74) *Attorney, Agent, or Firm* — Buche & Associates,
P.C.; John K. Buche; Bryce A. Johnson(57) **CLAIM**

I claim the ornamental design for a helmet, as shown and described.

DESCRIPTION

FIG. 1 is a front perspective view of a helmet showing my new design;

FIG. 2 is a front view thereof;

FIG. 3 is a rear view thereof;

FIG. 4 is a left-side view thereof;

FIG. 5 is a right-side view thereof;

FIG. 6 is a bottom view thereof;

FIG. 7 is a top view thereof;

FIG. 8 is a top perspective view thereof; and,

FIG. 9 is a cross-sectional view taken along line 9-9 in FIG. 6.

1 Claim, 6 Drawing Sheets(56)
